(57) **CLAIM**

The ornamental design for a ring, substantially as shown and described.

DESCRIPTION

FIG. 1 is a top perspective view of a ring showing my new design.

FIG. 2 is a rear elevational view thereof.

FIG. 3 is a front elevational view thereof.

FIG. 4 is a left side elevational view thereof.

FIG. 5 is a right side elevational view thereof.

FIG. 6 is a top plan view thereof.

FIG. 7 is a bottom plan view thereof, rotated 180 degrees; and,

FIG. 8 is a bottom perspective view thereof.

The broken lines illustrate environmental structure or portions of the ring and form no part of the claimed design.

1 Claim, 7 Drawing Sheets
